REVOLVING STORAGE BIN

Lawrence J. Nixon, Pittsburgh, Pa.

Application May 5, 1947, Serial No. 746,144

1 Claim. (Cl. 211—163)

1

This invention relates to a storage device for type metal feeder ingots.

It is an object of the present invention to provide a combined type metal feeder ingot storage device and conveyor for storing ingots from the time they are made to the time they are taken to the typesetting or typecasting machines wherein provision is made for automatically stopping and locking the storage platform at a predetermined point, and wherein the platform can be lifted from the supporting bearings to permit access to the space beneath the platform and to facilitate the cleaning of the top of the platform.

Other objects of the present invention are to provide a storage machine for type metal ingots, which is of simple construction, inexpensive to manufacture and efficient in operation.

For other objects, and for a better understanding of the invention, reference may be had to the following detailed description taken in connection with the accompanying drawing, in which

Fig. 1 is a top plan view of the storage device and of the lifting mechanism.

Fig. 2 is a cross-sectional view taken through the storage device and illustrating the operation of the lifting mechanism.

Fig. 3 is a detailed fragmentary view showing the hinge which is connected to the table to lift the same from its bearing supports.

Fig. 4 is a fragmentary and cross-sectional view taken through the table plate and looking in elevation upon the stop device for retaining the table against rotation.

Fig. 5 is a cross-sectional view taken through the spring stop for the table.

Fig. 6 is an end elevational view of the spring stop.

Fig. 7 is a cross-sectional view of the spring stop taken on line 7—7 of Fig. 5 and looking in the direction of the arrows thereof.

Fig. 8 is a side elevational view of the spring stop device showing the location of the stop pin at two different positions thereof.

Fig. 9 is a top plan view of a modified form of the invention.

Fig. 10 is a cross-sectional view taken on line 10—10 of Fig. 9 and looking in the direction of the arrows thereof.

Fig. 11 is a side elevational view of the storage device.

Fig. 12 is a top plan view of the ball bearing support for the storage device as viewed on line 12—12 of Fig. 10 and looking in the direction of the arrows thereof.

Fig. 13 is a bottom plan view of the member on

2

the storage device adapted to cooperate with the bearing support shown in Fig. 12.

Referring now particularly to Figs. 1 to 8, 21 represents a supporting base for a rotatable storage carrier 22 having a central upstanding tube 23 for storing metal and the platform lifting mechanism when this mechanism is not in use. The supporting base 21 has an annular portion 24 with a groove 25 therein for ball bearings 26 extending into a groove 27 of a ring 28 fixed to the bottom face of the carrier 22. A skirt 29 is secured to the outer periphery of the ring 28 and extends downwardly over the portion 24 to retain the carrier against lateral displacement on its support 21 and to act as a shield against dirt.

At spaced points on the platform of the carrier are holes 30 into which banking pins 31 may be placed. When the platform is revolving a pin so placed will strike a banking block 32 bringing the platform to a halt. This will happen when the pin illustrated in Fig. 4 is down all the way in the hole as shown in dotted lines, a substantial portion of it extending below the platform. However, the pin 31 may be held up by a spring 33 under the pin's head 35 to such a height that only a small portion of the pin extends below the platform. The upper edge at either end of the banking block, will engage the beveled end 34 of the pin, as the platform rotates, and raise the pin slightly. This releases the spring 33 which snaps back to its normal position indicated by the dotted lines. The pin, left without support, will ride atop the banking block to the other end where it will fall to its lowest position. If another pin 31 be placed all the way in the hole immediately behind this pin, the pin behind will strike the banking block at the rear end just as the pin in front falls at the front end to its lowest position. The platform will thus be halted and locked. The upper end of the spring 33, when the pin is raised, engages with a knurled flange 35 above which is a knurled lifting handle 36.

The spring device or banking block 32 comprises a channel member or outer casing 38 having open ends 39 bent inwardly to retain telescoping spring containers 41 and 42 housing a spring 43. The top of the casing 38 is open as indicated at 44 and through this opening banking pin 31 may pass until it is restrained by the action of the cushioning spring 43 acting within the container parts 41 and 42.

On the carrier 22 pipes 45 are extended outwardly from the center tube 23 and are supported at their outer ends by posts 46 extending upwardly from the carrier platform. Extending

through the posts 46 is an annular rail 47 formed in sections coupled with one another. Other rails can be extended through openings 48 in the pipes 45. These rails and pipes are arranged to support the pigs in an upright position upon the carrier.

In order that the carrier platform can be tilted upwardly at times in order to gain access to the thrust bearings on the support 21, there is provided at one side of the support 21, an upstanding portion 49 to which there is hinged a plate 51 as by means of a hinge pin 52. This plate 51 can be made secure to the carrier platform at these times by screws 53. The platform will then be hinged upon the pin 52 to assume a dotted line position as shown in Fig. 2. A weight 54 is secured as indicated at 55 to the upper end of a post 46 to assist in the upward movement of the carriage. While in the raised position, the carriage will be supported by a rod 56 fitted under the carriage and extended into an opening 57 in the support 21 and against a spring 58 lying within the opening. The rod 56 will be threaded in hole 61 in the platform 22.

Referring now particularly to Figs. 9 to 13, there is shown a modified form of the storage device wherein the support is of less diameter than the support of the previously described form of the invention. This support is indicated at 62 and is provided with a round top portion 63 in which there is a groove 64 for ball bearings 65. There is a support member 66 which is attached to carriage platform 67 by means of bolts 68. This support 66 has a projection 69 which extends through an opening 71 in the center of the support 62 to prevent tilting the platform 67 on support 62 and to prevent lateral displacement of the platform. A plate 72 and screw 73 fixes the projection within the opening 71. The support member 66 has a complementary groove for receiving the ball bearings 65 and also a ring 74 which extends down over the round portion 63 of the support 62 to shield the bearing from dirt.

Attached to the support 62 and extending radially therefrom is an arm 77 having an upstanding support 78 to which a plate 79 can be hinged by a pin 81 for the purpose of connecting the plate to the platform 67 to cause the same to be elevated from the support 62 at times when access is desired to oil the bearings. On the plate 79 there is fitted an upstanding member 82 having a hinge joint 83 with an arm 84 with a weight 85 thereon. By the use of this weight 85 and the arm 84 the platform can be easily and readily raised from the support.

The platform has the pins 31 for engaging with spring device 32 which is located upon the radially extending arm 77 of the support.

Radiating from the center of the platform are 60

a plurality of strong partitions 87 between which there are disposed openings 88 for receiving pigs 89.

While various changes may be made in the detail construction, it shall be understood that such changes shall be within the spirit and scope of the present invention as defined by the appended claim.

I claim:

10 An ingot holder comprising a supporting base, a platform journaled on said base and positioned to rotate in a horizontal plane thereon, supporting elements for carrying pigs positioned on said platform, a banking block having open slots in the ends mounted on said base, telescoping members positioned in said banking block, a spring in the telescoping members of the banking block for urging the telescoping members toward the ends of the block, said platform having spaced radially disposed holes therethrough and said holes positioned to correspond with the slots in the end of the block, pins with beveled lower ends and having heads on the upper ends adapted to be positioned in said holes of the platform, and spring fingers mounted adjacent said holes and adapted to extend inwardly under the heads of pins positioned in the holes, said spring fingers retained in position under the heads of the pins by the weight of the pins whereby upon engagement of the beveled lower ends of the pins with the upper edges of the ends of the banking block the pins are elevated and ride over the upper surface of the banking block thereby releasing the spring fingers so that upon reaching the far end of the block the pins drop to co-act with a following pin dropped through the next hole of the platform by hand for arresting and locking said platform.
